(57) **CLAIM**

What is claimed is the ornamental design for a turnstile, as shown and described.

DESCRIPTION

FIG. 1 is a perspective view of a turnstile in accordance with the present invention;

FIG. 2 is a front elevational view thereof;

FIG. 3 is a rear elevational view thereof;

FIG. 4 is a right-side elevational view thereof;

FIG. 5 is a left-side elevational view thereof; and,

FIG. 6 is a top view thereof.

The broken lines in the drawings depict portions of the turnstile that form no part of the claimed design.
